UNITED STATES PATENT OFFICE.

ARTHUR JUNGHANS, OF SCHRAMBERG, GERMANY.

MECHANICAL TIME-FUSE FOR ARTILLERY-PROJECTILES.

1,127,999.

Specification of Letters Patent.

Patented Feb. 9, 1915.

Application filed February 4, 1914. Serial No. 816,597.

To all whom it may concern:

Be it known that I, ARTHUR JUNGHANS, privy commercial councillor, a subject of the King of Wurttemberg, residing at Schramberg, Wurttemberg, Germany, have invented certain new and useful Improvements in Mechanical Time-Fuses for Artillery-Projectiles, of which the following is a full, clear, and exact description.

10 This invention relates to an improvement in or modification of the invention described in the specification of my U. S. Patent No. 1,069,094 dated July 29, 1913.

The essence of the invention described in my prior specification resides in the fact that the use of a spring as the actuating or controlling member is dispensed with, the necessary moments of force being obtained exclusively by means of centrifugal weights, 20 and the controlling of the driving force being effected in one case by means of a driving member dependent upon an additional centrifugal weight, and in the other case by an intermediate plate having a spiral periphery, co-operating with the centrifugal weight itself. It has been found necessary, however, to make provision for rendering a mechanical fuse of this type independent also of variations in the driving and controlling centrifugal forces due to deviations 25 of the longitudinal axis of the fuse from the axis of rotation of the projectile. The center of gravity of the driving centrifugal weight is located, as known, at a definite 30 distance from the longitudinal axis of the fuse (which under normal circumstances coincides with the normal axis of rotation of the projectile) and naturally this distance determines the force exerted by the centrif-

35 40 weight on the fuse mechanism, i. e., the driving force. When the projectile deviates from its normal axis of rotation, the fuse is displaced eccentrically with respect to the actual axis of rotation, and the driving force 45 naturally varies owing to the variation in the distance of the center of gravity of the weight from the axis of rotation, that is to say, the moment of force exerted on the mechanism varies. For instance, it may 50 happen that owing to such deviation, the axis of rotation may be located in the center of gravity of the driving weight itself, whereby the moment of force being zero, the mechanism will not be actuated. Conversely the farther the axis of rotation is 55 away from the center of gravity of the ac-

tuating weight, the greater will be the moment of force acting on the mechanism. It follows therefrom that according to the location of the center of gravity with respect to the real axis of rotation, or in other words, according to the eccentricity of the fuse, the driving moment varies between zero and the maximum. In order to eliminate this source of disturbance, the forces 60 exerted by the weights are distributed according to this invention, in such a manner that instead of a combined weight being provided, separate co-operating weights are arranged in pairs, to act as driving and 65 controlling weights, on either side of the axis of the fuse.

The drawing is a top-plan view of so much of a fuse mechanism embodying the present improvements as is necessary for an 70 understanding of the invention.

The invention is carried into effect in a simple manner by arranging two centrifugal drive weights A, B, symmetrically with respect to the longitudinal axis of the projectile, said weights being adapted to operate on the driving shaft C of the mechanism. Owing to this arrangement when the fuse is located eccentrically with respect to the normal axis of rotation of the projectile, the driving force of one weight will be increased and that of the other will be decreased to a corresponding extent. In this manner, the moment of force exerted on the driving shaft, or the sum of the separate 80 moments exerted by the separate weights, will remain constant under all conditions, i. e., in any position of the fuse with respect to the actual axis of rotation of the projectile. 85

In the application of the invention to the two constructions of time fuses described in the main patent, it follows that in the first case, where the control of the driving force is effected by means of an additional weight, 100 it is possible, as shown in the accompanying drawing, to sub-divide into two separate weights A, B the centrifugal driving weight, as well as to divide into separate controlling weights a, b, the additional weight required 105 for controlling the driving force and co-operating with the former. In the second case, where the control is effected by means of an intermediate plate, and in which therefore the control depends on the centrifugal driving weight itself, it is obvious that only the latter will be subdivided. In this

case, only one intermediate plate is provided in cooperation with a pair of toothed segments provided with centrifugal weights, and arranged symmetrically but occupying exactly the same position of engagement with respect to the axis.

What I claim as my invention and desire to secure by Letters Patent is:

1. A driving mechanism for time fuses for projectiles, comprising a driving shaft of a clock-work and a plurality of centrifugal elements, mounted symmetrically with respect to the longitudinal axis of the projectile, and adapted to receive force from the rotation of a projectile when fired from a gun, and to impart force to said driving shaft.

2. A driving mechanism for time fuses for projectiles, comprising a driving shaft of a clock-work, and a plurality of centrifugal elements, mounted symmetrically with respect to the longitudinal axis of the projectile, and adapted to receive force from the rotation of a projectile when fired from a gun, and to impart force to said driving shaft, and means for compensating for variations in the force exerted by said centrifugal elements.

3. A driving mechanism for time fuses for projectiles, comprising a driving shaft of a clock-work, and a plurality of centrifugal elements, mounted symmetrically with respect to the longitudinal axis of the projectile, and adapted to receive force from the rotation of a projectile when fired from a gun, and to impart force to said driving shaft, and means for compensating for variations in the force exerted by said centrifugal elements, said means comprising a weight in conjunction with each of said centrifugal elements adapted to act upon a centrifugal element through a variable moment.

4. A driving mechanism for time fuses for projectiles, comprising a driving shaft of a clock-work, and a plurality of centrifugal elements, mounted symmetrically with respect to the longitudinal axis of the projectile, and adapted to receive force from the rotation of a projectile when fired from

a gun, and to impart force to said driving shaft, and means having a variable moment for compensating for variations in said centrifugal elements.

5. A driving mechanism for time fuses for projectiles, comprising a driving shaft of a clock-work, and a plurality of centrifugal elements, mounted symmetrically with respect to the longitudinal axis of the projectile, and adapted to receive force from the rotation of a projectile when fired from a gun, and to impart force to said driving shaft, and means for compensating for variations in the force exerted by said centrifugal elements, said means comprising a weight in conjunction with each of said centrifugal elements, mounted symmetrically with respect to said longitudinal axis of the projectile.

6. A driving mechanism for time fuses for projectiles, comprising a driving shaft of a clock-work and a plurality of centrifugal elements pivotally mounted symmetrically with respect to the longitudinal axis of the projectile, and adapted to receive force from the rotation of a projectile when fired from a gun, and to impart force to said driving shaft.

7. A driving mechanism for time fuses for projectiles, comprising a driving shaft of a clock-work and a plurality of centrifugal elements pivotally mounted symmetrically with respect to the longitudinal axis of the projectile, and adapted to receive force from the rotation of a projectile when fired from a gun, and to impart force to said driving shaft, and means for compensating for variations in the force exerted by said centrifugal elements, said means comprising a weight in conjunction with each of said centrifugal elements pivotally mounted symmetrically with respect to said longitudinal axis of the projectile.

In witness whereof, I have hereunto signed my name in the presence of two subscribing witnesses.

ARTHUR JUNGHANS.
